CLAIM

The ornamental design for a set of gate brackets, as shown and described.

DESCRIPTION

FIG. 1 is a perspective view of a set of gate brackets taken from above and from one side showing my new design, the gate boards shown in phantom are not part of the design; FIG. 2 is an enlarged perspective view of the gate bracket shown in the lower right position in FIG. 1, the gate bracket shown in the upper right position in FIG. 1 being the mirror image thereof;

FIG. 3 is an enlarged perspective view of the gate bracket shown in the lower left position in FIG. 1, the gate bracket shown in the upper left position in FIG. 1 being the mirror image thereof;

FIG. 4 is a front elevational view of the gate bracket shown in FIG. 2;

FIG. 5 is a right side view of the gate bracket shown in FIG. 2;

FIG. 6 is a left side view of the gate bracket shown in FIG. 2;

FIG. 7 is a top view of the gate bracket shown in FIG. 2; FIG. 8 is a rear elevational view of the gate bracket shown in FIG. 3 with the hinge opened out 90° in comparison to the position shown in FIG. 3;

FIG. 9 is a right side view of the gate bracket shown in FIG. 8;

FIG. 10 is a top view of the gate bracket shown in FIG. 8; and,

FIG. 11 is a left side view of the gate bracket shown in FIG. 8.
